UNITED STATES PATENT OFFICE.

ERIC BERKELEY HIGGINS, OF WALLASEY, ENGLAND.

MIXING-MACHINE.

1,170,815.

Specification of Letters Patent.

Patented Feb. 8, 1916.

Application filed February 14, 1914. Serial No. 818,693.

To all whom it may concern:

Be it known that I, ERIC BERKELEY HIGGINS, Ph. D., a subject of the King of Great Britain and Ireland, residing at Wallasey, Cheshire, England, have invented certain new and useful Improvements in and Relating to Mixing-Machines, of which the following is a specification.

This invention relates to mixing machines adapted for the admixture of gases with liquids, and the invention has for its object to provide a mixing machine for this purpose of high efficiency and effectiveness.

The machine is more especially intended for use in the hydrogenation of fatty acids but is of general application in any case in which an intimate admixture of gases and liquids, of liquids and solids, or of various liquids or any other bodies whether solid, liquid or gaseous is desired to be expeditiously and thoroughly effected. The invention is applicable for example to the oxidation of liquids or solids with liquid mixtures such as for example the conversion of ferrous hydrate to ferric hydrate or to the drying of gases where the liquid in the mixer is a water absorbing liquid, or the scrubbing of gases.

According to the invention I provide the beaters or vanes with a number of conical cups closed at their bases and open at their narrower ends where they are mounted upon the plate forming the beater or vane. The plate is provided with a hole of corresponding size to that of the open end of the conical cup and the cup is mounted on the plate so that the opening in the cup is coincident with the hole in the plate. Such conical cups are uniformly distributed and are mounted upon one side of the beaters or vanes. Between the respective cups, however, holes are formed in the plate. These holes are advantageously arranged all over the plate so as to form continuous longitudinal and transverse rows of holes intermediate of the respective rows of conical cups. By such means on the rotation of the beaters or vanes the cups pass into the liquid open end first. A quantity of the gas thus becomes imprisoned in the cups and as the beater or vane rotates so does the liquid pass into the cup and the gas passes out. The gas continues to pass out throughout the course of the beater or vane through the liquid. Moreover, by the pro-

vision of holes intermediate of the cups in the manner described, the rush of the liquid through these holes carries the bubbles of gas through with it, and thus the bubbles of gas are brought into very intimate contact with the liquid.

The invention comprises the constructional features which are hereinafter described.

The invention is illustrated in the accompanying drawings in which—

Figure 1 is a cross section of a mixing machine, Fig. 2 is a sectional plan on the line A A (Fig. 1) showing also a sectional plan through the jacket on the line A¹, A¹ (Fig. 1).

According to the invention in its application to a mixing machine as illustrated adapted for the hydrogenation of fatty acids and the like, I provide a vessel *a* whose lower part is cylindrical in form and has mounted longitudinally therein the spindle *b* upon which the beaters or vanes *c* are carried. These beaters or vanes are constructed of a number of plates. These may advantageously be four in number disposed radially with reference to the lower part of the vessel and mounted equi-distant one from the other and maintained in that position by stays *c*¹ suitably disposed or by other means. The beaters or vanes *c* are provided with a number of conical cups *c*² closed at their bases and open at their narrower ends where they are mounted upon the plate forming the beater or vane. The plate is provided with a hole *c*³ of corresponding size to that of the open end of the conical cup and the cup is mounted on the plate so that the opening in the cup is coincident with the hole in the plate. Such conical cups are uniformly distributed and are mounted upon one side of the beaters or vanes. Between the respective cups, however, holes *c*⁴ are formed in the plate. These holes are advantageously arranged all over the plate so as to form continuous longitudinal and transverse rows of holes *c*⁴ intermediate of the respective rows of conical cups *c*².

By such means on the rotation of the beaters or vanes *c* the cups *c*² pass into the liquid open end first. A quantity of the gas thus becomes imprisoned in the cups *c*² and as the beater or vane rotates so does the liquid pass into the cup and the gas passes

out. The gas continues to pass out throughout the course of the beater or vane through the liquid. Moreover by the provision of holes intermediate of the cups in the manner described, the rush of the liquid through these holes carries the bubbles of gas through with it, and thus the bubbles of gas are brought into very intimate contact with the liquid. The beaters or vanes *c* are provided 5 of a length corresponding to that of the vessel so that thus in the rotation of the blades the liquid is compelled to pass through the holes provided in the beater or vane plates. The lower part of the vessel is provided 10 with a jacket *d* through which steam may be passed by means of the pipe *e* or other heating or cooling medium by means of which the operation may be effected at any desired temperature. The upper part of 15 the casing is advantageously extended beyond the path of the beaters or vanes and suitable fittings are provided for indicating the pressure within the casing, for the admission and outlet of gas and for the admission and outlet of the liquid. The vessel *a* is mounted upon two frames *f* which contact with the lower part of the vessel. Upon 20 the top faces of each of these frames are bolted angle irons *g* extending the length of the vessel on each side thereof, and these angle irons *g* are riveted to the sides of the vessel thus serving to prevent its displacement within the frames. The shaft *b* may 25 be rotated by any suitable gear. It will, however, be understood that the invention is not limited to these constructional details, but it is capable of being carried into effect in any form of casing and by the use of beaters or vanes of any particular form.

What I claim as my invention and desire to secure by Letters Patent is:—

1. A mixing machine, comprising a casing, beaters or vanes adapted to rotate within said casing, open cups of conical form mounted on said beaters or vanes, having their mouths at their smaller ends, the mouths of the said cups being disposed in the plane of the said beaters or vanes, substantially as described. 45

2. A mixing machine, comprising a casing, beaters or vanes adapted to rotate within the said casing so that their edges closely fit the inner walls of the said casing, open cups of conical form mounted on said beaters or vanes, having their mouths at their 50 smaller ends, the mouths of the said cups being disposed in the plane of the said beaters or vanes, said beaters or vanes being provided with series of holes intermediate of said cups, substantially as described. 55

3. A mixing machine, comprising a casing, a rotating shaft within said casing, beaters or vanes mounted upon said shaft at right angles thereto and so as in their rotation to fit the inner walls of the casing, open cups of conical form mounted on said beaters or vanes with their mouths disposed in line with the said beaters or vanes, said beaters or vanes being provided with series of holes intermediate of said cups, substantially as described. 60 65

In testimony whereof I have hereunto signed my name to this specification in the presence of two subscribing witnesses.

ERIC BERKELEY HIGGINS.
